UNITED STATES PATENT OFFICE.

VERN GILKEY, OF LOS ANGELES, CALIFORNIA.

HURDLE.

1,013,386.

Specification of Letters Patent.

Patented Jan. 2, 1912.

Application filed February 6, 1911. Serial No. 606,997.

To all whom it may concern:

Be it known that I, VERN GILKEY, citizen of the United States, residing at Los Angeles, in the county of Los Angeles and State of California, have invented a certain new and useful Hurdle, of which the following is a specification.

My invention relates to a hurdle and particularly to a hurdle convertible from a high into a low hurdle, one of the objects of my invention being to provide a simple hurdle for use on the rack track, which upon being struck by any portion of the body of an athlete while in the act of leaping over the same, will yield to the impact thus given and not fall over.

Another object of this invention is to provide a hurdle which may be built from the ground up presenting only straight outside lines so that when several hurdles are juxtaposed no space will be left between the tops of the hurdles into which a runner may place his foot when leaping over the same and thereby reduce the height of his jump.

With these and other objects in view, this invention consists of the features, details of construction and combination of parts described in connection with the accompanying drawing and then more particularly pointed out in the claims.

In the drawing—Figure 1 is a front elevation of my invention; Fig. 2 is a side elevation showing the high hurdle; Fig. 3 is a section on line X² X³ Fig. 1, showing the low hurdle.

The invention comprises two standards 1 mounted on base boards 2, which are conjoined by two horizontal boards 3¹, between which the said standards extend and to which they are fastened. The standards are additionally reinforced by members or plates 3 which are fastened to the uprights and also to the base boards 2. Pivoted between said standards or uprights 1, by pivot rod 4, is a frame 5, consisting of vertical studs 6 conjoined on top and bottom by horizontal strips 7 and 8 which are bolted to the

studs. In normal position, that is, when the high hurdle is desired for use, the strip 7 fits in the recesses 9 formed in the uprights, 50 thus keeping the frame 5 in position without however locking it so that it would not yield to slight impact. When using the low hurdle, the strip 8 is arranged to engage in the recesses 10 provided in the lower portion 55 of the uprights or standards 1.

As will be seen, the pivot does not extend centrally through the frame in order to give the two heights required for the hurdle, and while the frame 5 is disposed between the standards or uprights, the strips 7 and 8 are arranged to extend beyond the ends of the standards or uprights so that when alining several hurdles no spaces will be left between any of them.

What I claim is—

1. A hurdle comprising a plurality of vertical standards provided with recesses, base boards to which said standards are secured, a frame between said standards consisting of vertical studs and horizontal connecting strips, said strips extending beyond said studs and being arranged to engage the recesses in said standards to hold said frame in position of adjustment, and a pivot rod extending through said standards and through one end of said frame studs, whereby to afford a high or a low hurdle.

2. A hurdle comprising a plurality of vertical standards provided on both sides with recesses, and a frame pivoted eccentrically 80 between said standards, and consisting of vertical and horizontal strips, said horizontal strips extending beyond said vertical strips, and being arranged to engage the recesses in said standards, whereby the frame 85 may be normally held in position of adjustment.

In testimony whereof I affix my signature in the presence of two witnesses.

VERN GILKEY.
